UNITED STATES PATENT OFFICE.

JOHN McCUALEY, OF NEW YORK, N. Y.

FOLDING CRATE.

1,342,750.

Specification of Letters Patent.

Patented June 8, 1920.

Application filed May 15, 1917. Serial No. 168,803.

To all whom it may concern:

Be it known that I, JOHN McCUALEY, a citizen of the United States, residing at New York city, in the county of New York, 5 State of New York, have invented certain new and useful Improvements in Folding Crates; and I do hereby declare the following to be a full, clear, and exact description of the invention, such as will enable others 10 skilled in the art to which it appertains to make and use the same.

This invention relates to folding crates or boxes.

The object of the invention is to construct 15 a practical and simple crate for shipping purposes which embodies in one structure, all of the parts of the crate, so that when folded into a compact bundle, it will take up a minimum amount of space, and the 20 locking of the parts at a single point will insure the folded relation to the end of the return journey.

It is also an object of the invention to provide in a folding crate structure, a box, 25 which when set up, will possess a maximum degree of strength and rigidity, without the necessity of complicated or expensive fastening devices.

With the above objects in view, and such 30 others relating to the details of construction, as may hereinafter appear, my invention will now be fully set forth and described, reference being had to the accompanying drawings.

35 In the drawings:

Figure 1 is a plan view of the box or crate constructed in accordance with the invention set up with the lid sections closed,

Fig. 2 is a sectional view of the crate in 40 folded condition,

Fig. 3 is a longitudinal section through the box,

Fig. 4 is a transverse section therethrough,

Fig. 5 is a fragmentary section, and

45 Fig. 6 is a section on line 6—6 of Fig. 1.

Referring more particularly to the drawings, 1 represents a base which may be built upon suitable cleat members 2. Rising from the longitudinal sides of the base 1, are the 50 vertically disposed side members or bars 3, the vertical height of the bars 3 being slightly greater, or approximating, the net thickness of the ends 4, which, preferably

are also built up with the cleats 5. The cleats 5 provide an intermediate space with- 55 in which suitable handles 6 may be knocked down.

Hinged to the upper edges of the bars 3 are the sides 7, the hinges 8 thereof being secured across the inner faces of the sides 60 7 and bars 3 so that the sides will fold inwardly upon the outer faces of the ends 4. Since the ends 4 are of such length as to fold against the bottom 1 they must therefore fit between the bars 3 and the sides 7 65 when the latter stand in their open vertical positions. Located on the inner faces of the sides 7 are the eyelets 10 which are adapted to coöperate with the hooks 11 secured upon the inner faces of the ends 4 for engage- 70 ment with the eyelets when the sides and ends are extended. Sufficient spring or free play is allowed the sides 7 so that they may be sprung outwardly beyond the vertical to the slight degree which is necessary to per- 75 mit the extremities of the ends 4 to pass by the eyelets into their seated relation against the cleats 9.

The cover consists of the half sections 12 and 13 which are hinged along the upper 80 edges of the sides 7 by means of the three-leaf hinges 14, the middle leaves of the hinges 14 approximating the thickness of the elements 12 and 13, so that when the cover sections are thrown in their open posi- 85 tion, they will wholly clear the upper edges of the sides, and their free edges will come into the proper position for securing the crate in its knock down or folded condition. The cover section 12 is provided on its free 90 edge with a pair of recessed lock plates 15 with which a pair of hooks 16 may be engaged to lock the cover section in place, the hooks 16 being pivoted to the inner faces of the ends 4, so that when the crate is locked 95 it will be impossible to gain access to the fastenings for the section 12. The section 13 may be secured to the section 12, in their locked condition, by means of a pair of slide bolts 17 which are recessed longitudinally 100 into the cleats 18 of the cover section, the bolts entering into pockets 19 formed into companion cleats 20 of the cover section 12 and playing upon these bolts are friction springs 19^a to hold them adjusted. Thus, 105 when the crate is loaded and the covers are

drawn into closed position, the latter may be firmly secured in place. In order to lock or seal the crate, a hasp 21 is mounted to extend across the joints between the sections 12 and 13 for the application of a lock or seal.

In folding the crate, the cover sections 12 and 13 are first thrown backwardly against the sides 7, the ends 4 are then released and carried inwardly into contacting relation 10 with the inner face of the bottom 1. When the ends 4 are superimposed upon the bottom 1, their upper surfaces are flush with each other and after the inward folding of said ends the sides 7 will swing inwardly on the 15 same, the height of the sides being such as to place them in substantially contacting relation at their meeting edges along the middle of the box or crate. The sides 7 when folded inwardly have the cover sections 12 and 13 superimposed thereon, and connected to the side bars 3 are suitable hooks 22 and 23, which are adapted to engage in keepers 24, such as eye members carried upon the sections 12 and 13 of the 20 cover or lid, thereby locking the same against upward swinging movement and thus holding the crate knocked down or collapsed. 25

When the crate is set up for use a lock which is adapted to accompany the crate 30 may be engaged with the keeper for the hasp 21 carried upon the section 13 and which extends across the sections 12 and 13 in order to secure the crate or box closed

while loaded and when transported from one point to another.

35

The construction above described, provides a complete, practical and serviceable shipping device which is particularly adapted for use in the present increasing growth of parcel post trade, and fills the 40 demand for such a crate in this and other industries.

40

What I claim as my invention is:

A folding crate comprising a bottom, fixed side bars along its opposite longitudinal edges, inwardly foldable ends hinged to the bottom between the side bars, sides hinged to the side bars and foldable inwardly into the same plane with each other upon the ends when folded, cover sections swingingly connected to the upper edges of the respective sides and adapted to fold outwardly upon the sides when folded, hooks on the bars engaging eyes on the normally upper faces of said sections, a hasp on one cover section 50 engaging one of said eyes on the other when the box is set up and the cover closed, recessed lock plates in one section, and hooks pivoted inside said ends and engaging the lock plates when the box is set up.

50

In testimony whereof, I affix my signature in the presence of two witnesses.

JOHN McCUALEY.
